UNITED STATES PATENT OFFICE

143,436

DESIGN FOR A UTILITY HOLDER OR THE LIKE

Pietro Maniscalco and Peter Maniscalco, Jr.,
Chicago, Ill.

Application March 22, 1945, Serial No. 118,634

Term of patent 14 years

(Cl. D33—3)

To all whom it may concern:

Be it known that we, Pietro Maniscalco and Peter Maniscalco, Jr., citizens of the United States and residing at Chicago, county of Cook, and State of Illinois, have invented a new, original, and ornamental Design for a Utility Holder or the like, of which the following is a specification, reference being made to the accompanying drawing forming a part thereof.

Fig. 1 is a front elevational view of a utility holder or the like showing our new design;

Fig. 2 is an end elevational view thereof;
Fig. 3 is a top plan view; and,
Fig. 4 is a front perspective view thereof.

We claim:

The ornamental design for a utility holder or the like, as shown.

PIETRO MANISCALCO.
PETER MANISCALCO, JR.
